US0D1096126S

(12) **United States Design Patent** (10) **Patent No.:** **US D1,096,126 S**
(45) **Date of Patent:** **** Oct. 7, 2025**

(54) **CRUTCH**

(71) Applicant: **Zhongshan Bliss Medical Instrument Co., Ltd**, Guangdong (CN)

(72) Inventor: **Jiawang Mao**, Guangdong (CN)

(73) Assignee: **Zhongshan Bliss Medical Instrument Co., Ltd**, Guangdong (CN)

(**) Term: **15 Years**

(21) Appl. No.: **29/957,679**

(22) Filed: **Aug. 15, 2024**

(51) LOC (15) Cl. **03-03**

(52) U.S. Cl.

USPC **D3/8**

(58) **Field of Classification Search**

USPC D3/5, 7, 8, 9, 10; D12/133
CPC A61H 3/00; A61H 3/02; A61H 2003/0227;
A61H 2003/0233; A45B 9/00; A45B

2009/002; A45B 9/02

See application file for complete search history.

(57) **CLAIM**

The ornamental design for a crutch, as shown and described.

DESCRIPTION

FIG. 1 is a front, left-side perspective view of a crutch showing my new design;

FIG. 2 is a front, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof; and,

FIG. 7 is an enlarged view of a portion indicated with numeric 7 in FIG. 1.

The broken lines shown in the drawings depict portions of the crutch and form no part of the claimed design.

1 Claim, 5 Drawing Sheets
